UNITED STATES PATENT OFFICE.

JOSEPH STONE, OF BESSEMER, ALABAMA.

MOLD-RAMMING MACHINE.

Application filed December 3, 1923. Serial No. 678,216.

To all whom it may concern:

Be it known that I, JOSEPH STONE, a citizen of the United States, residing at Bessemer, in the county of Jefferson and State of Alabama, have invented certain new and useful Improvements in Mold-Ramming Machines, of which the following is a specification, reference being had therein to the accompanying drawings.

This invention relates to a mold ramming machine and it has for its object to provide a mechanism adapted to deliver a predetermined quantity of molding sand into a flask which has been superimposed upon a pattern frame to, then advance that flask to ramming position where the sand is acted upon by a plurality of angularly disposed peans or side rammers and thereafter is acted upon by a plurality of vertically acting butt ramers in such manner that the sand is tamped into the mold and about the patterns with great firmness and at such speed that great economy in operation is effected. The mechanism also comprises a plurality of gate reamers and means for expeditiously returning the pattern frame to the flask receiving position after the flask with the sand tamped therein has been removed from the pattern frame.

Further objects and advantages of the invention will be set forth in the detailed description which follows.

In the accompanying drawings:

Fig. 1 is a longitudinal sectional view of a machine constructed in accordance with the invention;

Fig. 2 is a partial transverse sectional view of the machine;

Fig. 3 is a detail view of the clutch controlling mechanism hereinafter described; and

Figs. 4 and 5 are views of alternative forms of pean lifting mechanism.

Like numerals designate corresponding parts in all of the figures of the drawings.

Referring to the drawings 5 designates the frame of the machine which is mounted upon track wheels 5^a, though it is manifest that it may be mounted upon other types of wheels without departure from the invention. Fixed side rails 6 are carried by the opposite side frame members 5, only one of which is shown, but, which, it will be understood is duplicated upon the opposite side of the machine and these rails constitute a track-way for a wheeled pattern frame 7.

This pattern frame carries patterns 8 and is adapted to receive upon its upper surface a flask 9. A sand hopper 10 is fed by a conveyor 11 and the sand hopper and the conveyor are all mounted upon extensions of the rails 6 so that the machine as a whole may be bodily moved toward the pile of sand as the sand is used. A rotary feeder 12 disposed in the sand hopper is so proportioned that upon a quarter turn of this feeder just the right amount of sand to properly fill the flask 9 is delivered into said flask. Thereafter a lateral lug 13^a on a conveyor flight 13 comes into contact with a lug 70 15 on the flask and the flask is caused to travel first along the rails 6 and then up a pair of rails 14 which are pivoted at 15' and which have a straight horizontal section 16 at their ends. The flight 13 forces the pattern frame and flask up the inclined ways presented by the rails 14 and onto the straight horizontal portion where the flight ceases to act upon the pattern frame and leaves said pattern frame in a position of rest upon 80 the upper ends of the rails 14 with the wheels of the pattern frame resting in indentations 16^a of the rails, by which the pattern frame is held against accidental movement. The operator then grasps the lever 85 17, see Fig. 3 and shifts it upon its pivot 18 to throw a clutch section 19 into engagement with a clutch section 20, the latter being carried by a pinion 21. This pinion is fast with the hub 22 of a pulley 23 which is 90 driven by a belt 24 from a motor 25. Since the clutch section 19 is splined upon a shaft 26 it follows that this will result in imparting rotation to said shaft and in imparting movement to cranks 27 carried by said shaft. 95 These cranks operate a set of side rammers or peans which serve to initially ram sand into the wedged shaped recesses presented by the inclined overhanging top walls of the flask. The shape of the top walls of this 100 flask is of importance because the side ramers or peans could not effectively compress the sand into the flask unless the sand was in a certain measure confined by the overhanging top walls and it will be seen that it 105 is the presence of these walls of this shape which provides wedge shaped recesses into which the peans may, by their ramming action, compress the sand. However, it is not to be understood that the invention is 110 limited to flasks having over-hanging top walls of the particular angle or shape shown,

because it is frequently the case that patterns of different shapes require flasks of different shapes and thus I contemplate making these peans of such construction that the angle upon which they act may be varied at will. Thus I have illustrated connecting rod 28 pivotally connected to the cranks at 29, the lower ends of said connecting rods having heads 30 at their lower ends which engage transverse pins 31 upon the upper ends of tubular sections 32 of the peans. These tubular sections slide through bearings 33 which bearings are rendered adjustable in arcs by being provided with ears in which arcuate slots are formed. Bolts 34 pass through these arcuate slots and take into the side frame members 5 of the machine. The bearing 33 is common to all of the tubular sections 32 on that side of the machine, it being manifest that when the angle is to be changed for one pean it must be changed for all of the peans. The pean heads 35 are mounted upon the lower ends of rods 36 which pass through bearing blocks 37, said blocks being pivoted at 38 in the side frame members 5 to permit of the change of angle above described. The rods 34 slide in the tubular sections 32 and these members, that is the rods 34 and tubular sections 32 are yieldingly connected by springs 40 which lie between and have their ends connected to collars 41 of the rods 34 and collars 42 of the tubular sections 32. Thus upon movement of the cranks 27 to withdraw the peans 35 from the flasks the springs serve as a positive connection to withdraw the heads 35. But they also act to provide a yielding connection during the ramming operation since it is manifest that as the sand is packed in under the inclined over-hanging walls 9^a of the flask the stroke must be shortened, since otherwise the ramming effect would be too severe. Under these conditions the springs provide the necessary yielding connection between these parts. The side ramers or peans upon the other side of the machine are constructed in the same manner and the same reference characters have been applied. These side ramers or peans are driven by cranks 26^a on a shaft 26^b which corresponds to the shaft 26 and the shaft 26^b is driven from shaft 26 by sprocket gearing 43. Referring now to Fig. 3 it will be seen that the pinion 21 meshes with a gear wheel 44 which carries a cam lug 45 on its face. I prefer to make the ratio of this gearing 3 to 1 but I may make it any desired ratio. The purpose of this construction is that when the side ramers or peans have made a predetermined number of strokes the cam lug 45 on gear wheel 44 will come in contact with the lever 17 and move it away from the gear 44 and disconnect clutch section 19 from the clutch section 20. This will throw the opposite end of the lever 17 in such di-

rection as to bring a clutch section 46, which is splined upon a shaft 47 into engagement with a clutch section 48 which is carried by a pinion 49, said pinion, in turn, being mounted upon the hub 50 of a pulley 51 over which the belt 44 passes. The result of this is to stop the shafts 26, 26^b and to set the shaft 47 into operation. This shaft drives through cranks 52 to a cross-head 53 which reciprocates vertically in ways 54 and actuates the top or butt rammers 55. These rammers are carried by rods 56 which having yielding engagement with the cross-head 53 through the medium of springs 58. After these butt rammers have made a predetermined number of strokes they are brought to rest due to the fact that the pinion 49, see Fig. 3, meshes with a gear wheel 60 which carries a cam lug 61 on its face and which cam lug in due season comes to a position where it acts upon the lever 17 to move it away from the gear 60 and to consequently throw the clutch section 46 out of engagement with the clutch section 48 the result of which is to bring the shaft 47 to rest. However, it should not be understood that the throwing of the clutch section 46 out of engagement with the clutch section 48 again throws the clutch section 19 into engagement with the clutch section 20 because the parts are so proportioned and arranged that the movement of the lever under the influence of the cam 61 is much less than the influence of said lever under the influence of the cam 45 so that when the cam 61 acts to throw clutch section 46 out it does not move the lever far enough to throw clutch section 19 in. In other words the action of cam 61 leaves the lever in a neutral position with all of the rammers at a position of rest and raised.

Then the operator draws the pattern frame and flask to the dotted line position illustrated in Fig. 1 or upon a pivoted track section 62 which is provided with a stop 63 against which the pattern frame comes to rest. This pivoted track section 62 is normally held against movement by a latch 64 which is actuated by a spring 65 to engage a pin 66 on the frame 5. With the track section 62 locked against movement said track section serves to aid in supporting the portion 16 of the track 14 during the ramming operation. This is due to the fact that the track section 62 is provided with a projection 62^a which underlies the free end of the track sections 14 during the ramming operation. When the pattern frame and flask have reached the dotted line position illustrated in Fig. 1, a hand lever 67 is grasped and pulled downwardly against the action of a spring 68 and this causes the descent of one or more gate reamers 69 by which the gates are formed in the sand. Then the flask with the sand therein is lifted from the pat-

tern frame, and the pattern frame is returned to position beneath the sand hopper 10 by kicking off the trigger 64 and tipping the track section 62 upwardly to bring their 5 inner ends into alignment with the right hand ends of rails 6, (Fig. 1). When this is done the pattern frame rolls down the inclined way presented and comes to a position of rest against stop 6^a and in position to 10 receive another flask which flask is to be filled with sand from hopper 10 preparatory to repeating the above described operation.

It is manifest that many ways may be devised for imparting movement to the parts and particularly for actuating the peans and it is to be understood that my invention covers any equivalent means for actuating these parts from the shafts 26, 26^b.

One method of actuating these peans is illustrated in Fig. 4 where the pean carrying rod is indicated at 75. This rod is slidably mounted in guides 76 and carries a tappet arm 77 adapted to be engaged and lifted 20 against the action of spring 78 by one or more lugs 79 carried upon endless flight or belts 80 which pass over pulley or sprocket wheels indicated diagrammatically at 81. It is manifest that as the lugs 79 ride out 25 of engagement with the tappet 77 the spring will force the pean rods down with a sharp, quick stroke. Thus the rods will be lifted more or less slowly and against the action of the spring but will be returned with a sharp, quick stroke.

Another construction for accomplishing this result is illustrated in Fig. 5 where a wiper cam 82 acts against a pin or lug 83 carried by the pean rod 84 and elevates it 30 against the tension of spring 85 which bears between a fixed guide 86 and a collar 87 carried by the pean rod. When the nose 88 of the cam rides out of engagement with the pin 83 the pean rod will be thrown downwardly with a sharp, quick stroke by spring 85 but will be raised more or less gradually 45 by the curved surface 89 of the cam.

It is further to be understood that the invention is not limited to the precise construction set forth in any respect but that it includes within its purview whatever changes fairly come within either the terms or the spirit of the appended claims.

Having described my invention what I 55 claim is:

1. A molding machine comprising a plurality of side rammers or peans acting at an angle, a plurality of top rammers and means which when set in operation cause the operation of the side peans for a predetermined number of strokes then cause said side peans to stop and set the top rammers in operation for a predetermined number of strokes and then bring said top rammers to rest.

65 2. In a molding machine the combination

with means for supporting a pattern frame and flask the latter having inclined and overhanging top walls, of a plurality of side rammers for ramming sand beneath the inclined top walls and a vertically operated 70 top rammer.

3. A structure as recited in claim 2 in combination with means for reciprocating all of said rammers.

4. A structure as recited in claim 2 in combination with driving means for the rammers and means for controlling said driving means in such manner as to permit initial operation of the side rammers and a subsequent interruption of said side rammers 80 and operation of the top rammers.

5. A structure as recited in claim 2 in combination with driving means for all of said rammers and clutch mechanism for controlling the driving means comprising a side 85 rammer clutch, a top rammer clutch and interconnecting elements therebetween acting to first shift the clutches to set the side rammers in operation and then interrupt the side rammers and set the top rammers in 90 operation and then interrupt the operation of the top rammers leaving all of said rammers idle and in elevated position.

6. The combination with a supporting frame, transverse shafts at the opposite end thereof, cranks carried by said shafts, side rammers operated by said cranks, a centrally disposed shaft above the frame, top rammers operated from the centrally disposed shaft, tracks carried by the frame and a pattern frame mounted to travel upon said tracks to a position within the frame where all of said rammers may cooperate therewith.

7. A structure as recited in claim 6 in 105 combination with a trackway for returning the pattern frame to its initial position.

8. In a machine of the character described the combination with a sand hopper constituting a filling station, a trackway leading therefrom, a pattern frame mounted to travel upon said trackway, a flask adapted to be mounted upon the pattern frame and to be filled from said hopper, a track section for conducting the pattern frame to an elevated position, a return trackway for conducting the pattern frame from said elevated position to the filling station and means for propelling the pattern frame 115 along the first named trackway to elevated position.

9. A structure as recited in claim 8 in combination with a tiltable track section upon which the pattern frame moves from the said elevated position and by which the pattern frame is discharged onto the return trackway.

10. A structure as recited in claim 8 in combination with a tilting track section upon which the pattern frame may be moved 130

and by which the pattern frame may be discharged to the return trackway and interengaging means between the tilting track section and the track section by which the pattern frame is conducted to elevated position, whereby the latter is supported by the former during the ramming operation.

11. A structure as recited in claim 8 in combination with a plurality of gate reamers and means for imparting downward movement to them.

12. In a machine of the character described, a sand hopper constituting a filling station, feeding means for delivering sand in predetermined quantities from said hopper, a pattern frame, a flask adapted to be mounted upon the pattern frame and receive sand from the hopper, a trackway upon which the pattern frame travels, a main frame by which the trackway is carried, an inclined pivoted trackway, means for propelling the pattern frame along the inclined pivoted trackway to a position within the main frame, a second pivoted trackway section, a latch for holding it against movement,

interengaging means between the two pivoted track sections, angularly operating side peans, said flask comprising inclined top walls beneath which said peans may be projected, cranks to which said peans are operatively connected and by which they are reciprocated, transverse shafts by which said cranks are carried, means for operating said shafts in unison, a motor constituting the driving means for said shafts, a vertically operating butt rammer and clutch connections between the butt rammer and the transverse shafts and means for operating said clutch connections in such manner that after the transverse shafts have made a predetermined number of revolutions, said clutch connections are shifted to throw said shafts out of operation and to set the vertical butt rammers in operation and for interrupting the operation of the butt rammer after it has made a predetermined number of movements.

In testimony whereof I hereunto affix my signature.

JOSEPH STONE.
